HAT BRIM FLANGING MACHINE

Henri H. Kaufman, New York, and Rudolph G. Segschneider, Yonkers, N. Y.

Application November 28, 1941, Serial No. 420,786

14 Claims. (Cl. 223—14)

This invention relates to hat brim flanging machines. It is particularly directed to a machine for flanging or shaping the brim of a felt hat from flat to curved shape, or for automatically molding the brim to a convex brim block.

An object of this invention is to provide in a flanging machine of the character described, having flanging means which act like the fingers of a human hand to press the brim of the hat against the brim block as the brim block rotates about the axis.

Yet a further object of this invention is to provide a machine of the character described, which may be heated either electrically or by gas burners, and in which the electric heating means are readily removable, should it be desired to heat the flanging fingers by the gas heater.

Yet another object of this invention is to provide a strong, durable and compact machine of the character described, which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side elevational view of a machine embodying the invention, with parts broken away and in cross-section, and showing the flanging apparatus in retracted position in dotted lines;

Fig. 2 is a top plan view thereof;

Fig. 3 is an enlarged, cross-sectional view taken on line 3—3 of Fig. 2;

Fig. 4 is a cross-sectional view taken on line 4—4 of Fig. 1;

Fig. 5 is a cross-sectional view taken on line 5—5 of Fig. 1;

Fig. 6 is a bottom plan view of the brim block; and

Fig. 7 is a top plan view of the brim block carrier.

Referring now in detail to the drawings, 10 designates a hat brim flanging machine embodying the invention. The same comprises a stand or support 11 having legs 12 and a top wall 13. The top wall 13 is formed with an opening 14, in which there projects a bearing 15 fixed to the

table top. Rotatably mounted in the bearing 14 is a vertical shaft 16.

Means is provided to rotate the vertical shaft 16. To this end, there is fixed adjacent the lower end of the shaft, a worm wheel 17. The stand or support is furthermore provided with a thrust bearing 18 to support the lower end of the shaft. Rotatably mounted in a pair of horizontally aligned bearings 19 on the support, is a transverse, horizontal shaft 20 carrying a worm 21 meshing with the worm wheel 17. On shaft 20 is a pulley 22. Supported on the bottom of the stand is an electric motor 25 connected by belt 26 to pulley 22.

15 It will now be understood that when the motor is operating, shaft 16 will be rotated about its axis through belt 26, and pulley 22, shaft 20 and worm wheel 17.

The upper end of shaft 16 projects above bearing 15. Mounted on the upper end of said shaft 16, is a carrier 30 for a hat brim block 31. The carrier 30 comprises a substantially elliptical bottom plate 32 connected to rotate with the shaft 16 in any suitable manner.

20 25 Mounted on the bottom wall 32 are four angularly spaced, upstanding brackets 33, to the upper ends of which is attached an elliptical ring 34. Fixed to the ring 34, are four upstanding pins 35. The brim block 31 is likewise substantially elliptical in shape, and has a flat undersurface 37 adapted to rest on top of the ring 34. The brim block 31 furthermore has an elliptical inner surface 38 and a convex outer and upper surface 39, of the shape it is desired to give the brim 40 of hat H.

30 35 On the underside of the block 31 are a plurality of vertical sockets 46, in which are fixed bushings or sleeves 47, adapted to receive the pins 35 on ring 34. The block may thus be mounted on ring 34 with the pins 35 received in the sleeves or bushings 47. When the motor operates, the brim block will rotate. The hat H may be mounted on the brim block in inverted fashion, as shown in Fig. 1 of the drawings with the crown of the hat projecting downwardly through the central opening in the brim block, and with the brim 40 of the hat contacting the convex surface 39 of the brim block.

40 45 50 Preparatory to flanging or shaping the brim of the hat, a piece of cloth 50 is placed over the brim of the hat, the cloth being clamped to the brim block by an annular coil spring 51. It will now be understood that the brim block rotates about its axis.

55 Means is provided to flange or shape the brim

40 of hat H to conform to the shape of the brim block, as the brim block rotates. To this end, there is mounted on the rear of the table top 13, a base 60 having longitudinal slots 61 extending to the outer ends of the base. The slots are in alignment with the axis of shaft 16. Screwed to the table top 13, are a pair of stud screws 62 passing through the slots 61, the heads of said screws contacting the upper surface of the base to firmly clamp the base to the table top 13. It will now be understood that the base 60 may be adjusted toward or away from the shaft 16, by loosening screws 62, for the purpose hereinafter appearing.

Base 60 is provided with a pair of spaced upwardly, apertured ears 60a carrying a transverse horizontal pivot pin 64. Pivotally mounted on pivot pin 64 is an arm 65 having ears 65a at the lower end thereof receiving the pivot pin 64. The ears 65a extend at right angles to the arm 65.

At the upper end of arm 65 is a U-shaped portion 66 disposed at an angle of about 120 degrees to arm 65. The U-shaped portion 66 comprises parallel arms 67 having ears 68 extending therefrom at right angles thereto. The ears 68 are apertured and support a transverse shaft 69. Fixed to one of the arms 67, and extending to one side thereof, is a horizontal handle 70 which may be grasped by a hand to swing arm 65 about its pivot 64.

Mounted on the transverse shaft 69, and suspended therefrom, between the arms 67, are a plurality of similar fingers 71 each comprising three knuckles 72, 73 and 74. The fingers 71 are parallel to each other and in side by side relation, and each is movable entirely independently of the others. Knuckles 72 are provided with through openings 75, through which the shaft 69 passes.

The knuckles 72 are formed with longitudinal through openings 76 disposed at right angles to the through openings 75, for the purpose hereinafter appearing. Said knuckles 72 are furthermore formed with curved front edges 77 substantially conforming to the shape or curvature of the top of the brim block, adjacent the inner surface 38 thereof. The knuckles 72 are furthermore formed with downwardly extending flanges 80 on one side thereof and of reduced width, and each formed with a through opening 81. The flanges 80 are substantially half the width of the body of the knuckles.

The knuckles 73 are formed with upwardly extending flanges 83 complementary to the flanges 80 and likewise formed with through openings 84 adapted to register with the through openings 81 to receive pivot pins or rivets 88. The flanges 83 of the knuckles 73 are likewise substantially half the width of the body of said knuckles. Knuckles 73 have front curved edges 90 which conform substantially to the curvature of a portion of the brim block, such portion being the portion between the top substantially horizontal portion of the brim block and the substantially vertical lower portion of the brim block. The knuckles 73 also have downwardly extending flanges 91 of reduced width and in alignment with the upwardly extending flanges 83 thereof, and likewise formed with through openings 92.

The bottom knuckles 74 have upwardly extending flanges 95 complementary to the flanges 91, and formed with through openings 96 to receive pivot pins 97 which serve to pivotally connect knuckles 73 to knuckles 74. Flanges 95 are likewise substantially half the width of the knuckles 74.

It will now be understood that the knuckles 72, 73 and 74 are of substantially the same width, except for the flanged portions thereof.

Each of the fingers 71 is suspended from the transverse shaft 69. When arm 65 is swung toward the brim block, the fingers will contact the cloth 50 and press against the brim of the hat. As the carrier rotates, the knuckles of the fingers will move back and forth, always pressing however, against the brim to flange or shape the same and mold the brim of the hat to the convex shape of the brim block.

It will be noted that the fingers act like the fingers of the human hand, all the fingers acting independently, and the knuckles or joints of each finger moving relatively, one to the other. The fingers may be made of copper or other metal having a relatively high capacity. The surfaces of the fingers which do the pressing or flanging are preferably curved somewhat transversely, so as not to present any sharp edges against the brim of the hat. The arm 65 may be swung forwardly or rearwardly by means of handle 70. The position of the fingers relative to the brim block may be adjusted by properly adjusting base 60 relative to the stand 11. Although the brim block is elliptical, it may rotate about its axis, and the fingers will nevertheless press against the brim to properly flange and shape the same.

Means is provided to heat the fingers electrically. To this end, an electric heater 100 is inserted into each of the openings 76, and retained therein by a set screw 101. Attached to the heaters 100 is the wiring 102 which may be received in a bracket 103 mounted on the U-shaped portion 66 of arm 65. The bracket 103 may be provided with a pair of loops 103a to receive the wiring. The heaters 100 may be readily removed by merely loosening the set screws 101 and pulling the heaters out of the openings 76. When the fingers are heated electrically, the heat will travel by conduction from the knuckles 72 to the knuckles 73 and then to the knuckles 74.

Means is provided to heat the fingers by gas heat. To this end, there is fixed to arm 65 a bracket 110 formed with a through opening, through which there passes a pipe 111. At one end of pipe 111 there is attached a pipe 113 running alongside of the arm 65. At the upper end of the pipe 113 is an elbow 115 disposed just below the U-shaped portion 66 of arm 65. Attached to elbow 115 is a pipe 116 located below the U-shaped portion 66, and closed at its outer end and formed with burner openings. On pipe 113 is an air inlet 120.

If it is desired to heat the fingers by gas, pipe 111 is connected by a flexible pipe 121 to a supply of gas. If the fingers are heated electrically, the flexible pipe 121 is disconnected and the pipes 111, 113 and 116 remain fixed to the arm 65 and move therewith.

Means is provided to increase the pressure of the fingers on the brim of the hat. To this end, there is fixed to substantially the middle of arm 65 a loop or ring 125, on which any suitable weight W may be hung to additionally press the fingers against the brim during the flanging operation.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter here-

in set forth or shown in the accompanying drawings is to be interpreted as illustrative and not in a limiting sense.

Having thus described our invention, we claim as new and desire to secure by Letters Patent:

1. In a flanging machine, a brim block, means to rotate the block about its axis, and means to press the brim of a hat against the brim block, said last means comprising a movable member, a shaft on said member, and a plurality of fingers each pivotally suspended at one end thereof, only, from said shaft, the opposite end of each finger hanging freely, each of said fingers comprising a plurality of interpivoted knuckles, said fingers being adapted to be moved against the brim block.

2. In a flanging machine, a brim block, means to rotate the block about its axis, and means to press the brim of a hat against the brim block, said last means comprising a movable member, a shaft on said member, a plurality of fingers each pivotally suspended at one end thereof, only, from said shaft, the opposite end of each finger hanging freely, each of said fingers comprising a plurality of interpivoted knuckles, said fingers being adapted to be moved against the brim block, and means to heat said fingers.

3. In a flanging machine, a brim block, means to rotate the block about its axis, and means to press the brim of a hat against the brim block, said last means comprising a movable member, a shaft on said member, a plurality of fingers each pivotally suspended at one end thereof, only, from said shaft, the opposite end of each finger hanging freely, each of said fingers comprising a plurality of interpivoted knuckles, said fingers being adapted to be moved against the brim block, means to heat said fingers, and a weighted member on said movable means to press said fingers against the brim block.

4. In a brim flanging machine, a shaft, a finger suspended at only one end thereof from the shaft and the opposite end of said finger hanging freely, said finger comprising a knuckle pivoted on said shaft, a second knuckle pivoted to the first knuckle, and a third knuckle pivoted to the second knuckle and being otherwise freely suspended.

5. In combination with a brim block, and means to rotate the same, brim flanging means comprising a member, a plurality of fingers each suspended at only one end thereof from the shaft and the opposite end of the finger hanging freely by gravity, each of the fingers comprising interpivoted knuckles, and means to move said member to bring said fingers against the brim block.

6. In a brim flanging machine, a base, an arm pivoted thereto, a transverse shaft carried by said arm, and a plurality of fingers freely pivotally suspended on said shaft and disposed in parallel relation, each of said fingers comprising a plurality of interpivoted knuckles, and being supported at one end only and otherwise freely hanging from said shaft.

7. In a brim flanging machine, a base, an arm pivoted thereto, a transverse shaft carried by said arm, a plurality of fingers freely pivotally suspended on said shaft and disposed in parallel relation, each of said fingers comprising a plurality of interpivoted knuckles, and being supported at one end only and otherwise freely hanging from said shaft, and a handle on the upper end of said arm to swing said arm relative to its pivotal connection to said base.

8. In a brim flanging machine, a base, an arm pivoted thereto, a transverse shaft carried by said arm, a plurality of fingers freely pivotally suspended on said shaft and disposed in parallel relation, each of said fingers comprising a plurality of interpivoted knuckles, and being supported at one end only and otherwise freely hanging from said shaft by gravity, a handle on the upper end of said arm to swing said arm relative to its pivotal connection to said base, a knuckle on each finger being formed with an opening, and electric heaters within said openings.

9. A machine for flanging the brim of a hat, comprising a stand, a vertical shaft rotatably mounted thereon, a carrier at the upper end of the shaft connected thereto for rotation therewith, a brim block mounted on said carrier, the axis of said shaft being co-axial with the axis of the brim block, an arm pivoted to said stand about an axis perpendicular to said shaft, a plurality of fingers freely pivotally suspended from said arm, said fingers comprising interpivoted members adapted to press against the brim block upon pivotally moving the arm toward said block, and said fingers being supported only at one end and otherwise hanging freely by gravity.

10. A machine for flanging the brim of a hat, comprising a stand, a vertical shaft rotatably mounted thereon, a carrier at the upper end of the shaft connected thereto for rotation therewith, a brim block mounted on said carrier, the axis of said shaft being co-axial with the axis of the brim block, an arm pivoted to said stand about an axis perpendicular to said shaft, a plurality of fingers each pivotally suspended at one end from said arm, said fingers comprising interpivoted members adapted to press against the brim block upon pivotally moving the arm toward said block, said fingers being disposed in parallel, side by side relation, and being independently movable, and said fingers being supported only at one end and otherwise hanging freely by gravity.

11. A machine for flanging the brim of a hat, comprising a stand, a vertical shaft rotatably mounted thereon, a carrier at the upper end of the shaft connected thereto for rotation therewith, a brim block mounted on said carrier, the axis of said shaft being co-axial with the axis of the brim block, an arm pivoted to said stand about an axis perpendicular to said shaft, a plurality of fingers each pivotally suspended at one end from said arm, said fingers comprising interpivoted members adapted to press against the brim block upon pivotally moving the arm toward said block, said fingers being disposed in parallel, side by side relation, and being independently movable, one or more of the interpivoted members in each finger having curved edge portions conforming substantially to the curvature of portions of the brim block, and said fingers being supported only at one end and otherwise hanging freely by gravity.

12. A machine for flanging the brim of a hat, comprising a support, a brim block mounted on the support for rotation about its axis, a member pivoted to said support about an axis perpendicular to the axis of the brim block, a shaft carried by said member, and disposed parallel to the pivotal axis for said member, and a plurality of fingers each pivotally suspended at one end from said shaft, each finger comprising a plurality of interpivoted portions, movable against said brim

block, said fingers being each supported at only one end and otherwise hanging freely by gravity.

13. A machine for flanging the brim of a hat, comprising a support, a brim block mounted on the support for rotation about its axis, a member pivoted to said support about an axis perpendicular to the axis of the brim block, a shaft carried by said member, and disposed parallel to the pivotal axis for said member, a plurality of fingers each pivotally suspended at one end from said shaft, each finger comprising a plurality of interpivoted portions, movable against said brim block, said fingers being parallel to one another, and made of metal, and means to heat said fingers, said fingers being each supported at only one end and otherwise hanging freely by gravity.

14. A machine for flanging the brim of a hat,

comprising a support, a brim block mounted on the support for rotation about its axis, a member pivoted to said support about an axis perpendicular to the axis of the brim block, a shaft carried by said member, and disposed parallel to the pivotal axis for said member, a plurality of fingers each pivotally suspended at one end from said shaft, each finger comprising a plurality of interpivoted portions, movable against said brim block, said fingers being parallel to one another, and made of metal, and means to heat said fingers, said fingers being each supported at only one end and otherwise hanging freely by gravity.

15. A machine for flanging the brim of a hat, comprising a support, a brim block mounted on the support for rotation about its axis, a member pivoted to said support about an axis perpendicular to the axis of the brim block, a shaft carried by said member, and disposed parallel to the pivotal axis for said member, a plurality of fingers each pivotally suspended at one end from said shaft, each finger comprising a plurality of interpivoted portions, movable against said brim block, said fingers being parallel to one another, and made of metal, and means to heat said fingers, said fingers having portions conforming in shape to the shape of said brim block, said fingers being each supported at only one end and otherwise hanging freely by gravity.

comprising a support, a brim block mounted on the support for rotation about its axis, a member pivoted to said support about an axis perpendicular to the axis of the brim block, a shaft carried by said member, and disposed parallel to the pivotal axis for said member, a plurality of fingers each pivotally suspended at one end from said shaft, each finger comprising a plurality of interpivoted portions, movable against said brim block, said fingers being parallel to one another, and made of metal, and means to heat said fingers, said fingers having portions conforming in shape to the shape of said brim block, said fingers being each supported at only one end and otherwise hanging freely by gravity.

HENRI H. KAUFMAN.

RUDOLPH G. SEGSCHNEIDER.
